UNITED STATES PATENT OFFICE.

HOWARD M. DUDLEY, OF PHILADELPHIA, PENNSYLVANIA.

FABRIC-TREATING MACHINE.

1,331,743.

Specification of Letters Patent.

Patented Feb. 24, 1920.

Application filed February 18, 1918. Serial No. 217,789.

To all whom it may concern:

Be it known that I, HOWARD M. DUDLEY, a citizen of the United States, residing in the city of Philadelphia, county of Philadelphia, and State of Pennsylvania, have invented certain new and useful Improvements in Fabric-Treating Machines, of which the following is a full, clear, and exact specification.

10 My invention relates to fabric treating machines and refers particularly to devices suitable for the treatment of rolled fabrics with liquids.

The dyeing, bleaching and similar treatments of textile fabrics, are frequently accomplished by rolling or winding the fabric upon foraminous cylinders and forcing the liquid through the thus wound fabric.

In order to produce even and equal results 20 in all parts of the fabric, it is necessary that the flow of liquid be uniform through all portions thereof.

As the flow of the liquid through the fabric has a tendency to force the fabric outwardly of the roll, it is essential that the 25 fabric be maintained in a uniform and constant state of compression during the operation.

In order to produce uniform results, it is 30 also essential that all of the liquid be forced uniformly through the fabric roll, and special care must be exercised that this is accomplished along the edges of the roll, in order that the treatment at this part of the 35 fiber may be the same as that of the interior portions.

It is also desirable that the fabric may be wound directly upon the foraminous dyeing reel without removing the latter from 40 the remainder of the treating device, and that several reels of fabric be dyed at the same time under the same conditions.

It is further desirable that the condition 45 of the fabric be capable of determination without interrupting the operation or disturbing the fabric being treated.

The device of my invention accomplishes 50 all of these objects and presents a simple, economical and effective method of producing uniform results throughout the entire fiber roll.

In order that the flow of liquid may be 55 the same through all parts of the fabric, I close all openings in the foraminous cylinder except those portions covered by the fabric and in order to protect the edges of the roll,

I cause an imperforate body to abut upon all portions thereof. My device also presents a means whereby the fiber roll is maintained under pressure and free from movement during the treating process.

As it is practically impossible to roll fabric so that the edges of the rolls will present an absolutely even surface, my device comprises a series of movable members which 65 may be caused to abut the edge of the roll so as to overcome any inequalities therein and close all passages through which the liquid might pass other than through the entire fabric roll.

The means for closing a portion of the foraminous cylinder, for preventing the passage of liquid except through the entire roll and for maintaining the roll in a compressed condition during the treatment are clearly 70 shown in the specification and by the drawings herewith which also disclose means whereby several rolls of fabric may be treated at the same time and under the same condition.

I have also found that valuable commercial results are obtained when the fabric has a dye liquid forced through it in one direction and drawn through it in the reverse direction. The results thus obtained 75 are more uniform than those obtained by forcing the liquid through the fabric in the two directions, as the drawing of the liquid causes a more or less rearrangement of the 80 passages through which the liquid passes, 90 and hence, those portions of the fabric which may not be properly dyed when the liquid passes in one direction, will receive proper treatment when the liquid passes through in the reverse direction.

The process of alternately forcing and drawing a dye liquid through a fabric therefore produces more valuable results than can be produced where the liquid is forced through it in both directions.

In the accompanying drawings illustrating modifications of my device, similar parts are designated by similar numerals:—

Figure 1 is a top plan view of one form of my device.

Fig. 2 is a cross-section through the line 105 2—2 of Fig. 4.

Fig. 3 is a cross-section through the line 3—3 of Fig. 4.

Fig. 4 is a cross-section through the line 110 4—4 of Fig. 2.

Fig. 5 is a broken enlarged vertical cross-

section showing a portion of the means for closing the openings in the foraminous cylinder.

Fig. 6 is a view in the direction of the 5 arrows of the line 6—6 of Fig. 5.

Fig. 7 is a cross-section through the line 7—7 of Fig. 8.

Fig. 8 is a broken top plan view of a portion of the foraminous cylinder.

10 Fig. 9 is a fragmental enlarged detail section taken on line 9—9 of Fig. 10.

Fig. 10 is a cross-section through the line 10—10 of Fig. 9.

15 Fig. 11 is a broken vertical cross-section of the interior of a modified form of a reel.

Fig. 12 is a cross-section through the line 12—12 of Fig. 11.

Fig. 13 is a broken cross-section through the line 13—13 of Fig. 4.

20 Fig. 14 is a side plan view of one of the cover blades.

The particular form of my device illustrated in the accompanying drawings comprises a receptacle formed by the end walls 25 20 and 21, the side walls 22 and 23, the bottom 24 and the top 25 hinged to the side wall 23 at 26, 26. Within the receptacle are two revoluble reels each comprising an end member 27, the foraminous cylindrical member 30 28 and the hollow conical member 29 which is extended into the hollow cylindrical member 30. The member 30 is revoluble within the bushed bearing 31 of the wall 21, and revoluble around the branch 32 of the pipe 33

35 within the bushed bearing 34. The member 27 of the reel carries the inwardly extended imperforate member 35 and is fixedly attached to the shaft 36, revoluble within the bushed bearing 37 of the wall 20. Revoluble around the shaft 36 is the bevel gear 38, meshing with the bevel gear 39 fixedly attached to the shaft 40 revoluble within the bearing 41 supported by the wall 20. The shaft 40 carries the fixed pulley 42 connected 40 to a source of revoluble power, not shown. The toothed clutch 43 is revoluble with the shaft 36 and carries a spline 44, movable along the longitudinal recess 45 of the shaft 36. Revoluble within the supports 46, 46 is 45 the rod 47, to which is fixedly attached the finger member 48 encompassing a recess within the clutch 43, so arranged that the revolution of the rod 47 will move the clutch 43 and engage it with teeth 38' on the gear 38. The rod 47 carries the handle 49, by means of which it may be revolved.

In order to close a desired portion of the openings in the foraminous cylinder 28 of the reel, a device as shown in broken form 60 in Fig. 5 is employed. An annular flange 50 is fixedly attached to the member 27. Abutting upon the imperforate and foraminous portions of the reel cylinder and slidably thereon is an annular member 51. A right 65 and left turn-buckle 52 connects the mem-

bers 50 and 51. Within a recess 53 of the member 51 is a series of concentric annular members 54, 54, abutting upon each other and forming watertight engagement therewith. Springs 55, 55 surrounding the pins 52', 52' abut upon the members 54, 54 and the member 51. This portion of the device is therefore so formed that the member 51 and the lower member 54 cover a portion of the foraminous cylinder 28 closing all of 75 the openings in the portion thus covered. A similar device is fixedly attached to the other end 29 of the cylinder.

The foraminous cylinder comprises a series of upwardly and downwardly extended 80 pyramidal members, the sides of which are composed of the triangular members 60, 60, a series of openings 62, 62 being situated at the juncture of the bases of the triangles 60, 60.

Attached to each cylindrical member 30 is a testing device shown in detail in Fig. 9. The testing device contains one reel similar to one of the larger ones, and in Fig. 9 similar parts are designated in prime numerals. The cylindrical portion 70 of the testing reel carries the pipe 71 which is connected to the interior of the member 30 and carries the valve 72. The member 27 carries the pipe 73, having the openings 74, 74, 95 carrying the valve 75 and opening into the chamber 76 of the larger device. The top 77 of the testing device may be removed from the bottom 78 by removing the screw bolts 79, 79. The pipe 80 connects the pipe 100 33 with the second reel.

A foraminous cover capable of placement around the fabric 100 and of holding it in position during its treatment comprises a series of serrated blades, each blade consisting of two portions 120, 120, overlapping each other and being connected by the springs 121, 121, thus allowing the blades 120, 120 to be moved longitudinally. These blades fit into grooves in the annular end 110 members 122, 122, which are hinged at 123, 123 and capable of being clamped at 124, 124.

The pipe 33 carries the valve 90 and is connected with the discharge end of the rotary pump 91. The upper portion, or chamber, 76 of the receptacle is connected to the upper portion of the dissolving tank 92 by means of the pipe 93, carrying the valves 94 and 95. A pipe 96, carrying the valve 97, connects the pipe 93 with the receiving end 120 of the rotary pump 91, and is connected to the bottom of the dissolving tank 92 by the pipe 98 carrying the valve 99. A pipe 101, carrying the valve 102, connects the upper portion of the receptacle with the discharge 125 chamber of the reciprocating pump 103, and the receiving chamber of the reciprocating pump 103 is connected to the pipe 33 by the pipe 104, carrying the valve 105. A pipe 130, carrying the valve 131, is connected 130

with the discharge chamber of the rotary pump 91.

The operation of the device is as follows:—

5 The top 25 is opened and fabric 100 is wound upon one of the foraminous cylinders by moving the arm 49, engaging the clutch 43 with the gear 38. Revoluble motion is thus transmitted to the reels through the 10 medium of the revolving gear 39, and the fabric thus wound thereon. The revolution of the reels is then interrupted. The foraminous cover is then placed around the fabric and clamped thereon, and the annular 15 members 51, 51 are moved slidably over the reel by means of the turn buckles 52, 52, the members 54, 54 abutting upon the sides of the wound fabric 100, and closing all of the openings in the foraminous cylinder except 20 those upon which the fabric abuts. The testing device is opened, the reel removed, wound with fabric 100' and replaced. The top 25 is closed and all of the valves are closed with the exception of valves 98, 90, 25 94, 95, 72, 72, 75 and 75 and the pump 91 started, the liquid thus passes from the dissolving tank 92 through the pipe 96, the rotary pump 91, the pipes 33, 32, 80, 30, 30 into the reel, whence it is forced through the 30 foraminous cylinder and the fabric 100 wound thereon into the receptacle, from which it passes through the pipe 93 into the tank 92 for continuous circulation. At the same time the liquid is forced through the 35 pipes 71, 71 into the reel within the testing device, through the fabric 100' therein and through the pipe 73 into the large receptacle.

When it is desired to reverse the current of liquid, the pump 91 is stopped, valves 90 40 and 94 are closed, valves 102 and 105 are opened and the reciprocating pump 103 is started. The liquid is now drawn from the receptacle, through the fabric 100 into the interior of the reel and thence through the 45 pipes 30, 30, 32, 80, 33 and 104 into the pump 103 whence it is returned to the receptacle by means of the pipe 101 for continuous circulation. The flow of liquid is likewise reversed through the testing device.

50 When desired, the condition of the fabric may be determined by closing valves 72 and 74, opening the top 77 and examining the fabric 100'.

The reels may be revolved during the 55 treatment, if desired, or they may be allowed to remain at rest.

Liquid may be drained from the large device through the pipe 130 and from the testing device through the pipe 132.

60 In the modification of the interior of the reel shown in Figs. 11 and 12, a series of concentric annular walls 140, 140 extend inwardly from the member 29 and flare outwardly until they abut upon the inner surface of the reel cylinder. The walls 140, 140

are supported by a series of supporting bars 141, 141.

I do not limit myself to the particular size, shape, number or arrangement of parts as described and shown all of which may be varied without going beyond the scope of my invention as described and claimed.

What I claim is:—

1. In a fabric treating machine, in combination, a receptacle, a series of revoluble 75 hollow foraminous reels within the receptacle capable of having fabric wound thereon, means for revolving any reel while the others are maintained in non-revoluble position, means slidable upon the reels and capable of closing some of the openings therein, means for continuously forcing a liquid outwardly from the interior of each reel through fabric wound thereon and means for continuously drawing a liquid into the 80 interior of each reel through fabric wound thereon.

2. In a fabric treating machine, in combination, a receptacle, a series of hollow foraminous reels within the receptacle capable of having fabric wound thereon, means 90 slidable upon the reels and capable of closing some of the openings therein, means for simultaneously forcing a liquid from the interior of the reels outwardly through fabric wound thereon and means for simultaneously drawing a liquid into the interior of the 95 reels through fabric wound thereon.

3. In a fabric treating machine, in combination, a receptacle, a series of revoluble 100 hollow foraminous reels within the receptacle capable of having fabric wound thereon, means for revolving any reel while the others are maintained in non-revoluble position, means slidable upon the reels and capable of closing some of the openings therein, 105 slidable means capable of abutment upon the edge of fabric wound upon the reels, means for continuously forcing a liquid outwardly from the interior of each reel 110 through fabric wound thereon and means for continuously drawing a liquid into the interior of each reel through fabric wound thereon.

4. In a fabric treating machine, in combination, a receptacle, a series of hollow foraminous reels within the receptacle capable of having fabric wound thereon, means 115 slidable upon the reels capable of closing some of the openings therein, a foraminous 120 cover capable of adjustment around fabric wound upon the reels, maintaining it from disarrangement during the passing of liquid therethrough, means for simultaneously forcing a liquid from the interior of the 125 reels outwardly through fabric wound thereon and means for simultaneously drawing a liquid into the interior of the reels through fabric wound thereon.

5. In a fabric treating machine, in com- 130

bination, a receptacle, a series of revolute hollow foraminous reels within the receptacle capable of having fabric wound thereon, means for revolving any reel while the others are maintained in non-revolute position, means slideable upon the reels and capable of closing some of the openings therein, slideable means capable of abutment upon the edge of fabric wound upon the reels, a 5 foraminous cover capable of adjustment around fabric wound upon the reels, maintaining it from disarrangement during the passing of liquid therethrough, means for continuously forcing a liquid outwardly 10 from the interior of each reel through fabric wound thereon and means for continuously drawing a liquid into the interior of each reel through fabric wound thereon.

6. In a fabric treating machine, in combination, a receptacle, a series of revolute hollow foraminous reels within the receptacle capable of having fabric wound thereon, means for revolving any reel while the others are maintained in non-revolute position, means slideable upon the reels and capable of closing some of the openings therein, series of concentric members slideable over each other and capable of abutment upon the edge of fabric wound upon the 20 reels, means for forcing a liquid from the interior of the reels outwardly through fabric wound thereon into the receptacle and means for drawing a liquid from the receptacle inwardly through fabric wound upon the 25 reels into the interior of the reels.

7. In a fabric treating machine, in combination, a receptacle, a series of revolute hollow foraminous reels within the receptacle capable of having fabric wound thereon, means for revolving any reel while the others are maintained in non-revolute position, means slideable upon the reels and capable of closing some of the openings therein, series of concentric members slideable over each other and capable of abutment upon the edge of fabric wound upon the 30 reels, a series of longitudinally spaced blades 35

slidable over each other and capable of abutment upon the outer face of each roll of fabric wound upon the reels, means for forcing a liquid from the interior of the reels outwardly through fabric wound thereon into the receptacle and means for drawing a liquid from the receptacle inwardly through fabric wound upon the reels into the interior of the reels.

8. In a fabric treating machine, in combination, a receptacle, a series of revolute hollow foraminous reels comprising a series of outwardly extended pyramidal members with openings therein within the receptacle capable of having fabric wound thereon, means for revolving any reel while the others are maintained in non-revolute position, means slideable upon the reels capable of closing some of the openings therein, means for continuously forcing a liquid outwardly from the interior of each reel through fabric wound thereon and means for continuously drawing a liquid into the interior 55 of each reel through fabric wound thereon.

9. In a fabric treating machine, in combination, a receptacle, a series of revolute hollow foraminous reels comprising a series of outwardly extended pyramidal members 60 with openings therein within the receptacle capable of having fabric wound thereon, means for revolving any reel while the others are maintained in non-revolute position, means slideable upon the reels and capable of closing some of the openings therein, series of concentric members slideable over each other and capable of abutment upon the edge of fabric wound upon the 65 reels, means for forcing a liquid from the interior of the reels outwardly through fabric wound thereon into the receptacle and means for drawing a liquid from the receptacle inwardly through fabric wound upon the 70 reels into the interior of the reels.

Signed at New York in the county of New York and State of New York this 14th day of February, 1918.

HOWARD M. DUDLEY
